(57) **CLAIM**

The ornamental design for a sealable cup having storage, as shown and described.

DESCRIPTION

FIG. 1 is an isometric projection of a sealable cup having storage of my new design.

FIG. 2 is a front elevational view of the sealable cup having storage of FIG. 1.

FIG. 3 is a rear elevational view of the sealable cup having storage of FIG. 1.

FIG. 4 is a right side elevational view of the sealable cup having storage of FIG. 1.

FIG. 5 is a left side elevational view of the sealable cup having storage of FIG. 1.

FIG. 6 is a top plan view of the sealable cup having storage of FIG. 1; and,

FIG. 7 is a bottom plan view of the sealable cup having storage of FIG. 1.

The broken lines shown in the drawings are for illustrative purposes only and form no part of the claimed design.
